United States Patent Office

Des. 180,442
Patented June 11, 1957

180,442

CRADLE

Michael Domizio, West Palm Beach, Fla.

Application August 31, 1956, Serial No. 42,805

Term of patent 3½ years

(Cl. D5—5)

Fig. 1

Fig. 2

I claim:

The ornamental design for a cradle, as shown.
